UNITED STATES PATENT OFFICE.

LEE M. VANCE, OF DAVIS, CALIFORNIA, ASSIGNOR, BY DIRECT AND MESNE ASSIGNMENTS, TO THE VANCE COMPANY, INCORPORATED, OF DAVIS, CALIFORNIA, A CORPORATION OF CALIFORNIA.

CONCRETE-POST MACHINE.

1,148,063.

Specification of Letters Patent.

Patented July 27, 1915.

Application filed October 22, 1912. Serial No. 727,258.

To all whom it may concern:

Be it known that I, LEE M. VANCE, a citizen of the United States, residing at Davis, in the county of Yolo and State of California, have invented certain new and useful Improvements in Concrete-Post Machines, of which the following is a specification.

This invention relates to an improvement 10 in molds for concrete fence posts.

The primary object of the invention is to provide a mold which may be adjusted to vary the dimensions and design of the post.

A further object of the invention is to provide 15 a construction in which the operator may simultaneously apply pressure to the pallet and the top of the mold.

A further object of the invention is to provide 20 a post ejecting mechanism, the ejecting members of which will be supported flush with the pallet and which may be operated to raise the post above the side walls of the mold.

Another object of the invention is to provide 25 means for imparting movement to the pallet throughout its length which may be operated from both ends of the mold.

Another object of the invention is to provide 30 means for limiting the movement of the pallet.

A still further object of the invention is to provide an actuating means for the movable parts of the mold and the post ejecting mechanism which may be operated from 35 one end of the mold, the actuating levers being disposed so that the mold sections may be brought in contact with the concrete and the ejecting mechanism manipulated by one operator.

40 In the drawings: Figure 1 is a side elevation; Fig. 2 is an end elevation; Fig. 3 is a section on the line 3—3 of Fig. 1; Fig. 4 is a horizontal section on the line 4—4 of Fig. 3; Fig. 5 is a section on the line 5—5 45 of Fig. 4, the mold being shown as in its open position; Fig. 6 is a transverse section, the mold being shown in its closed position; Fig. 7 is a detail view of one of the end members; Fig. 8 is a detail view of the base member which is supported by the spaced 50 supporting members. Fig. 9 is a transverse section showing the means for raising the pallet.

Corresponding and like parts are referred

to in the following description and indicated 55 in all the views of the drawings by the same reference characters.

In the drawings, 10 designates the supporting frame which includes a plurality of supports 11. These supports 11 are each 60 formed with a vertically extending portion 12 and with feet 14. The supports at their upper ends are each provided with the substantially U-shaped frame 15, the portions 16 thereof which form connections between 65 the U-shaped frame and the uprights 12, being formed with openings to receive bolts 17. The supporting members 11 are of a number consistent with the length of the mold, said members being disposed in spaced relation, 70 their frames 15 supporting the longitudinal base member 18 which is formed with the central web portion 19 and the extensions or flanges 20, said flanges being provided with openings 21 through which bolts 22 pass, as 75 indicated in Fig. 5. Plates 23, which are formed with a plurality of apertures 24, are secured on the portions 16 of the frames 15 by bolts 17 inserted through said apertures 24 and the openings in said portions 16. 80 The sides of the mold consists of plates 25, the upper edges of which are provided with longitudinal flanges or offsets 26 disposed to rest upon the plates 23, bolts 27 passing through the said flanges 26 and through 85 said plates. The lower edge of each side plate 25 is flanged or offset, as at 28, said offset being more extensive than the flange or offset 26 and provided with apertures 90 which receive the bolts 21. By this construction the side plates 25 are adjustable 95 transversely with respect to the plates 23 and base member 18, the plates 23 being adjustable on the intermediate portions 16 of the supporting members to space the plates 25 so that the post formed in the mold will have the desired width. A pallet 30 is supported on the offsets 28, said pallet adjacent the sides of the mold being formed with tapered or inclined walls 31, attention being 100 called to the fact that these walls may be of any suitable configuration to vary the design of the post.

The base member 18 is formed with a series of vertical openings 32, through which 105 extend rods 33 which contact with the under face of the pallet. Movement is imparted to these rods in a manner which will be

hereinafter described to raise and lower the pallet to vary the thickness of the post 34. The member 18 is also provided with a second series of vertical apertures 35 through 5 which extend rods 36. These rods are provided at their upper ends with disks 37 which are received within openings 38 formed in the pallet, the upper faces 39 of said disks being then disposed flush with 10 the face of the pallet. The rods 36 are raised after the post has been molded, the disks 38 serving as ejectors to raise the post out of the mold.

The pallet lifting rods 33 are actuated by 15 levers 40 which are connected to the rod 41 which is suitably mounted for reciprocatory movement in the main supporting frame. The levers 40 are pivotally connected to the rod 41, a plurality of levers 42 connecting 20 said rod with collars 43 which embrace the shaft 44. This shaft 44 is supported for rocking motion on the main frame, the shaft turning freely within the collars 43. The rod 41 is reciprocated by means of the levers 25 45 to raise and lower the pallet supporting rods 33. These levers 45 are pivotally supported by brackets 46 and connected by links 47 with the rod 41. It will be noted that as 30 the lever 45 is moved in one direction the levers 40 and 42 will be disposed at right angles to the rod 41 and that the pallet will be raised.

The end sections 50 of the mold consist 35 of U-shaped plates, the portion 51 which connects the side walls 52 thereof contacting with the end of the post and the terminals 53 being secured to the portions 20 of the base member 18.

By the construction thus far described, 40 the sides, bottom and end sections of the mold are provided.

The top of the mold, which is movable vertically, consists of the longitudinal beam 54 on the lower edge of which the top section 54' is carried, the beam being suspended 45 for a vertical movement by a beam 56 to which is pivotally connected a plurality of links 57. These links are connected to the rod 58 which is connected by a plurality of links 59 with the beam 54. The rod 58 is actuated by means of the lever 60 which is pivotally supported at 61 by the beam 56.

It will be noted that as the lever 60 is 55 moved on its pivot the bar or beam 54 will be raised and lowered by means of the links 59. The top section 54' is guided in its vertical movement by the rods 55, the section being formed with the apertured ears 62 through 60 which the rods 55 extend and said rods being rigid with and rising from the supports 11 at the end of the mold. It will thus be noted that the top section may be raised and lowered in a simple and convenient manner, the terminal 63 of the lever 65

60 being disposed adjacent the terminal 64 of the lever 45. It will be seen by this construction that the pallet and the end sections of the mold, as well as the top section, may be conveniently manipulated from 70 one end of the mold, pressure being exerted on the base and top of the mold simultaneously.

With the mold arranged as shown in Fig. 5, the concrete is tamped in place. The lever 60 is then actuated to force the top section in contact with the concrete, after which the levers 45 and 60 may be moved to cause the pallet and the top section to approach each other whereby the concrete will 75 be compressed and the post formed.

When the post has been molded and it is desired to remove the same from the mold, the mold ejecting members are actuated. The mold ejecting rods 36 are connected to 80 the recurved link 65, the lower terminal of which is connected to the lever 66 which is secured to the shaft 44 whereby the ejecting members, which are disposed throughout the length of the mold, may be actuated, movement being imparted to the shaft by the lever 67, the terminal of which is disposed adjacent the terminal 64 of the lever 45. It will be seen by this construction that 85 after the post has been molded, the mold may be opened and the post raised to a position where it may be removed, the entire manipulation of the operating mechanism being accomplished from one end of the mold. 90

The many advantages in a construction of this character will be clearly apparent as it will be noted that the construction is such as may be easily and economically manufactured and that the sections which form the mold may be readily adjusted to vary the size of the post. It will also be seen that the mold sections may be provided with members for forming posts which vary in design and that the adjustment of the sections may be accomplished without removing the sections from the mold. 100

Having thus described the invention, what is claimed as new is:

1. A mold comprising a series of aligned supporting members, a stationary base member supported by and extending longitudinally of said supporting members, side sections extending longitudinally of said supporting members and having inturned lower ends secured to the base member and having their upper ends secured to the supporting members, a pallet resting on the lower ends of the side members, means for imparting vertical movement to the pallet, and a top section supported for vertical movement. 115

2. A mold comprising spaced supporting members, a stationary base member rigidly secured to and extending longitudinally of said supporting members, said base member 120

- being formed with vertical openings, pallet-raising members extending through said openings, a pallet extending over said pallet-raising members, side sections rigidly secured at their lower ends to the stationary base member and at their upper ends to the spaced supporting members, the lower edges of the said side sections extending inwardly beneath the pallet, rigid end sections secured to the base member at the ends of the pallet, a top section arranged to fit between the side sections and the end sections, means for actuating the pallet raising members, and means for moving the top section.
- 5 3. A mold comprising a supporting structure, side sections supported by said structure, a stationary base member, a pallet supported over said base member, plungers disposed beneath said pallet and extending through and guided by the base member, means for imparting vertical movement to the said plungers to lift the pallet, other plungers extending through the base member and adapted to extend through the pallet, disks carried by the upper ends of said last mentioned plungers and lying flush with the pallet when lowered, a shaft disposed longitudinally of the supporting structure, levers mounted on said shaft and connected 20 to the last mentioned plungers, and means for rocking said shaft to raise said plungers.
- 10 4. A mold comprising a supporting structure, side sections resting against the inner faces of and supported by said structure, end-sections, a stationary base member secured to the side sections, a pallet supported over said base member, pallet-raising plungers extending through the base member to contact with the under face of the pallet, means for imparting movement to said plungers, ejector plungers extending through the base member and adapted to extend through
- 25 the pallet, disks carried by the upper ends of said plungers and lying normally flush with the upper face of the pallet, and means for imparting movement to said plungers.
- 30 5. A mold comprising a supporting frame, side-sections secured thereon, a base member secured to the lower ends of the side sections, rigid end sections on the base member, a pallet disposed over the base member between the side and end sections, plungers extending through the base member to bear against the lower side of the pallet, ejector plungers extending through the base member and the pallet, a rock shaft mounted in the supporting frame below the base member, collars loosely mounted on said shaft, pivotally connected levers connected to and extending between said collars and the first mentioned plungers, a reciprocatory rod connected to said levers at the pivotal connections between the same, levers rigid with the rock-shaft, and links connecting said last mentioned levers with the ejector plungers.
- 35 6. A mold comprising a series of pairs of standards, U-shaped members secured to and extending between the upper ends of the standards of each pair, a base member resting on the lower portions of said U-shaped members, side sections secured to the base member and the upper ends of the U-shaped members, end-members secured upon the base-member, a pallet extending longitudinally over the base-member, means extending through the base member to raise and lower the pallet, and ejectors extending through the base member and the pallet.
- 40 In testimony whereof I affix my signature in presence of two witnesses.
